tion of Pennsylvania

Application February 20, 1948, Serial No. 8,688

15 Claims. (Cl. 230—1)

1

This invention relates to fluid compressing apparatus of the type embodying a storage reservoir and an air compressor for compressing air into said reservoir and one object of the invention is to provide an improved apparatus of this type.

Another object of the invention is the provision of improved means for cooling the compressed air delivered by the air compressor before it is forced into the storage reservoir.

Another object of the invention is the provision of improved means for cooling the compressor air discharge valves to minimize injury thereto by the high temperature of the air discharged by the compressor.

Another object of the invention is the provision of improved means for automatically unloading the compressor each time it is shut down.

Another object of the invention is the provision of improved means for automatically draining condensate from the storage reservoir each time the compressor is shut down.

Other objects and advantages will be apparent from the following more detailed description of the preferred embodiment of the invention taken together with the accompanying drawing forming a part of the specification.

In the drawing, the single figure is a diagrammatic view, mainly in section, illustrating the preferred embodiment of the invention.

Description

As shown in the drawing, the fluid compressing apparatus comprises an air compressor 1, a cooling coil 2, an unloading and drain valve device 3, a small reservoir 4 and a large storage reservoir 5 provided in a casing 6 and separated by a partition wall 7, and a cut-off valve device 8. A pipe 9 extending from a discharge valve chamber 10 of the compressor 1 is connected through the cooling coil 2 to the unloading and drain valve device 3. A pipe 11 connects the unloading and drain valve device 3 to the large reservoir 5 while a pipe 12 connects said valve device to the small reservoir 4.

The fluid compressing apparatus further comprises a pipe 13 connecting the discharge valve chamber 10 in the air compressor 1 to the cut-off valve device 8 and a pipe 14 connecting said cut-off valve device to the reservoir 5.

Considering the parts of the equipment in greater detail, the compressor 1, which may be of the reciprocating type and driven in any suitable manner, comprises a discharge valve 15 contained in chamber 10 and arranged for co-

2

operation with a seat 16 formed in a cylinder head 18 which is mounted over the upper end of a cylinder bore 19, said bore being encircled by a gasket 20 which prevents leakage of fluid under pressure between the upper end of said bore and the atmosphere. The valve 15 is urged to its seat by a spring 21 disposed between said valve and a cap 22 having screw-threaded engagement with the cylinder head 18. The cap 22 is provided with a recess 23 in constant communication with the discharge valve chamber 10 through one or more notches 22a in the lower end of said cap, and a series of bores 24 in said cap connect said recess with a chamber 25 formed in the cylinder head 18 and to which the pipe 13 is connected.

The cooling coil 2 comprises a sufficient length of pipe disposed between the discharge valve chamber 10 and the unloading and drain valve device 3 to provide for a certain transfer to atmosphere of heat from compressed air discharged by the compressor 1 past the discharge valve 15 to said pipe so that by the time the said compressed air reaches said valve device its temperature will be considerably lower than that leaving the discharge valve chamber 10.

The unloading and drain valve device 3 comprises two casing sections 26 and 27 secured to each other and to an end cover 28 common to both of said casing sections. Casing section 26 is provided with a chamber 29 to which the cooling coil 2 is connected, and a smaller chamber 30 having a connection with the atmosphere through a choke 31. The chambers 29 and 30 are connected by a bore 32 in which is disposed a valve stem 33 having at one end a valve 34 disposed in chamber 30 for controlling communication between said chambers by way of a passage 40. The opposite end of stem 33 is connected centrally with a diaphragm 35, clamped around its edge between casing section 26 and cover 28, by means of two diaphragm followers 36 and 37 and a nut 38 having screw-threaded engagement with the stem 33. One side of diaphragm 35 is exposed to pressure of air in chamber 29 and the opposite side to pressure of air in a chamber 51.

The casing 27 is provided with a chamber 41 which is adapted to be connected to the chamber 29 by a bore 52. The casing 27 is also provided with two spaced apart and coaxially arranged valve seats 43 and 44, and the connection between chamber 41 and bore 42 is through the valve seat 43. Provided in the chamber 41 between the valve seats 43, 44 is a flat disc type

valve 45 which is adapted at one time to seat on the seat 43 and at another time to seat on the seat 44. Disposed between the valve 45 and a wall 46 separating chambers 28 and 41 and through which the bore 42 is provided is a spring 47. With the valve 45 resting on the seat 44 the distance between the top surface of the valve and the wall 46 is greater than the free height of the spring 47 so that said spring will be out of contact with the wall 46. The distance between the top of the spring 47 and the wall 46 is less however than the distance between valve seats 43 and 44 so that when the valve 45 is moved into engagement with the valve seat 43 the spring 47 will be compressed a certain chosen amount which depends on the free height of said spring.

The chamber 41 is connected to the reservoir 4 by the pipe 12, which together with bore 42, chamber 28, cooling coil 2 and pipe 9, provides a fluid pressure communication between said reservoir and the discharge valve chamber 10 when the valve 45 rests on seat 44.

A chamber 48 formed in the casing section 27 beneath the valve seat 44, is connected to the reservoir 5 by means of a passage 49 and the pipe 11. A branch passage 50 connects the passage 49 to chamber 51 formed at the left hand side of the diaphragm 35 so that the pressure in the reservoir 5 is always present in said chamber.

The cut-off valve device 8 comprises a casing 52 having a bore 53 and a counterbore 54. Disposed in these bores in a differential type piston 55 comprising a larger piston 56, the diameter of which is slightly less than that of bore 53 to permit a limited flow of fluid under pressure therewith, and a smaller piston 57 on which is provided a valve 58 for cooperation with a seat 59 formed at the upper end of counterbore 54, to control communication between said bores. The larger piston 56 divides the bore 53 into a lower chamber 61 and an upper chamber 60, to which latter chamber the pipe 14 is adapted to be connected at a point just above the top of said larger piston when said piston occupies a lower position in which it is shown in the drawing.

The differential type piston 55 is provided with a large counterbore 62 open to chamber 60 and a small bore 63 connecting said counterbore to chamber 66 below valve 58. The bore 63 is provided near its upper end with a valve seat 64. A ball-type check valve 65 is provided for cooperation with the seat 64 to control a by-pass communication around the valve 58 between chamber 66 below the said valve and the chamber 60. Disposed in the bottom of counterbore 62 is a spring seat 67 having a bore 68 to provide a fluid pressure communication between chambers 60 and 66 when the check valve 65 is raised from its seat. Disposed between the spring seat 67 and a cap 69 having screw-threaded engagement with the casing 52 is a spring 70 for urging the differential type piston 55 to its lower position with the valve 58 seated.

The reservoir 5 is provided with an outlet pipe 71 for supplying fluid under pressure to any location where it may be desired to use the same.

Operation

With the various parts of the fluid compressing apparatus in the position in which they are shown in the drawing and with no fluid under pressure in the apparatus, atmospheric pressure will be present on both sides of the diaphragm 35 of the unloading and drain valve device 3 so

that the valve 34 may be either seated or unseated. Upon starting the compressor 1 fluid under pressure will be discharged past the valve 15 to the chamber 10 from whence it will flow through the pipe 8 and cooling coil 2 to the chamber 28, wherein it will act on diaphragm 35 to urge it in the direction of the left hand for seating the valve 34, if not already seated. If the valve 34 is initially open there will be a flow of fluid under pressure from chamber 28 through passage 40, past the valve 34, and through chamber 30 and choke 31 to the atmosphere. Since the capacity of the choke 31 is less than the capacity of the compressor 1, the fluid under pressure being supplied to the chamber 28 at the right hand side of the diaphragm 35 will promptly provide a pressure on said diaphragm which so exceeds the atmospheric pressure acting on the left hand side thereof as to deflect said diaphragm in the direction of the left hand carrying with it the stem 33 and the valve 34 until said valve engages its seat which will thereby terminate flow of fluid under pressure to the atmosphere through the choke 31.

With the valve 34 closed, the fluid under pressure supplied to the chamber 28 by the compressor 1 will flow through the bore 42, chamber 41 and pipe 12 to the reservoir 4 thereby increasing the pressure in said reservoir.

A portion of the fluid under pressure flowing past the discharge valve 15 to chamber 10 will flow through the recess 23 and bores 24 in the cap 22 to the chamber 25 and thence through the pipe 13 to the chamber 66 of the cut-off valve device 8. The capacity of bore 63 in the cut-off valve device 8 is considerably less than the displacement of the compressor 1 so that only a small portion of the fluid compressed by the compressor can escape past ball check valve 65 to the chamber 60 and thence through the pipe 14 to the large reservoir 5, the major portion of the air compressed by the compressor being displaced into reservoir 4, as above described, while the cut-off valve 58 is seated. Therefore the pressure of fluid in chamber 66 will gradually increase along with that in reservoir 4 until such pressure in said chamber acting on the cut-off valve 58 provides a force so exceeding the opposing force on said valve including spring 70, as to unseat said valve. Upon unseating the cut-off valve 58 fluid under pressure in the chamber 66 will flow past said valve to the chamber 61 where it acts on the lower side of the larger piston 56 outside of the smaller piston 57 to provide an increased upwardly acting force on said pistons to snap said pistons upwardly until said larger piston strikes the cap 69 which arrest further upward movement of said pistons.

At the time the differential type piston 55 comes to rest against the cap 69 the bottom of the large piston 56 will be above the connection of the pipe 14 to the chamber 60 which permits a rapid flow of fluid under pressure from the chamber 66 through the chamber 61 and pipe 14 to the reservoir 5.

The flow of fluid under pressure from the chamber 66 to the reservoir 5 results in a decrease in the pressure in said chamber. As the pressure decreases in chamber 66, fluid under pressure in the reservoir 4, which is at the same pressure as that in the chamber 66 at the time the valve 58 was opened, flows back through pipe 12, chamber 41, bore 42, chamber 28, cooling coil 2, pipe 9, chamber 10, recess 23, bores 24, chamber 25, pipe 13, chamber 66, past the open valve 58 and through the pipe 14 to the reservoir 5.

As the pressure of fluid in reservoir 5 builds up as above described, the pressure of fluid in chamber 60 above the piston 58, which pressure was initially the same as in reservoir 5, may build up past the check valves 65 and by leakage past the piston 58, and hence will equalize substantially with that in pipe 14 and in said reservoir. When the pressure of fluid in chamber 60 and in reservoir 5 is thus increased sufficiently with respect to the pressure of fluid in chamber 66 the spring 70 will start moving the piston 58 downwardly and such movement will continue under the reducing pressure of spring 70 in proportion to the reducing differential between the pressures in chambers 66 and 60 until eventually the cut-off valve 58 will reseat which it is desired will occur when said differential is of some chosen value such as five pounds. When the cut-off valve 58 is thus reseated further flow of fluid under pressure from reservoir 4 to reservoir 5 is prevented except for that past the check valve 65.

When the cut-off valve 58 is closed as just described, the pressure of fluid in chamber 61 surrounding the smaller piston 57 reduces by equalizing past piston 58 to that present in chamber 60 and reservoir 5 whereby only the smaller piston 57, which controls opening of the cut-off valve 58 as previously described, is subject to the increasing pressure of fluid in chamber 66.

By reason of the fact that the area of the piston 56 is larger than the area of the piston 57, it will be evident that the pressure at which the valve 58 closes will be less than that at which it opens, this pressure differential being dependent on the relative diameters of the two pistons.

When the pressure of fluid in the reservoir 4 and chamber 66 in the cut-off valve device 8 again becomes increased to a degree sufficient to open the cut-off valve 58 against spring 70 and the pressure of fluid in chamber 60, the cut-off valve will again open to permit flow of fluid under pressure from reservoir 4 to reservoir 5 until the pressure in the latter reservoir is increased to with perhaps five pounds of that in reservoir 4 whereupon the cut-off valve 58 will again close in the manner above described. In this manner the pressure of fluid in reservoir 5 will be increased and maintained by successive charges of fluid under pressure from the reservoir 4.

The time elapsing between the instant at which the cut-off valve 58 closes and that at which it opens again provides for a certain amount of cooling of the fluid under pressure being supplied to the reservoir 4 by radiation from the outside surface of said reservoir, due to the fact that the temperature of the atmosphere surrounding said surface is considerably lower than that of the fluid under pressure being supplied to said reservoir by the compressor 1. Therefore, due to the cooling of the fluid under pressure produced by flowing through the cooling coil 2 to the reservoir 4 and subsequently from said reservoir to reservoir 5 and that produced by radiation of heat from the outside surface of the reservoir 4, the fluid under pressure supplied to reservoir 5 from reservoir 4 at the time the valve 58 opens, is considerably cooler than that being delivered by the compressor 1 past the discharge valve 16, and effects a cooling of said discharge valve in flowing over said valve in its passage from the reservoir 4 to the reservoir 5 in the manner which has been previously explained. Thus it is seen that the fluid under pressure compressed by the compressor 1 will be cooled to a certain degree before it is discharged into the large reservoir 5 from

5
whence it may be conducted through the pipe 11 to the point where it is used. At the same time the cooling of the fluid under pressure is utilized to keep the temperature of the discharge valve 16 and discharge valve chamber 10 below a dangerous value.

During the time that the compressor 1 is operating, the fluid under pressure discharged therefrom and present in the chamber 41 maintains the valve 45 seated on its seat 44, since the discharge pressure in said chamber is greater than the pressure in the reservoir 5, tending to unseat said valve, thereby preventing flow to the reservoir 5 through the pipe 11. However, fluid under pressure from the reservoir 5 flows through the pipe 11 and branch passage 50 to the chamber 51, but since the higher compressor discharge pressure is present in the chamber 29 the diaphragm 35 is operated thereby to hold the valve 34 seated.

When the compressor 1 is shut down the fluid under pressure in the reservoir 4 equalizes with that in the reservoir 5 past the ball check valve 65 in the cut-off valve device 8. When the pressures in the two reservoirs become equal the pressures on both sides of the diaphragm 35 will be the same and the fluid under pressure present in the chamber 29, which is compressor discharge pressure, and acting through the passage 40 in bore 32 on one side of valve 34 will unseat said valve since only atmospheric pressure is present in the chamber 30 acting on the opposite side of said valve. With the valve 34 unseated the fluid under pressure in the chamber 29, cooling coil 2, pipe 9, discharge chamber 10, pipe 13 and chamber 66 in the valve device 8 flows past said valve and through the choke 31 to the atmosphere, the check valve 65 and seated cut-off valve 58 holding the fluid under pressure in reservoir 5. At the same time fluid under pressure from the reservoir 4 will flow through the pipe 12, chamber 41 and bore 42 to the chamber 29 and thence through the choke 31 also to the atmosphere.

As soon as the pressure in the chamber 41 has fallen slightly below the pressure in chamber 48, which pressure is the same as that in the reservoir 5, the higher pressure in chamber 48 will unseat the valve 45 from its seat 44 and move it, together with the spring 47 which rests thereon, upward until said spring contacts the wall 46. The spring 47 will then be compressed by the further flow of fluid under pressure from the chamber 41 to the atmosphere until the valve 45 seats on the seat 43. With the valve 45 thus seated on the seat 43, further flow of fluid under pressure from the reservoirs 4 and 5 to the atmosphere is prevented and reservoir 4 is connected to the reservoir 5 through pipe 12, chambers 41 and 48, passage 49 and pipe 11 permitting the fluid under pressure in both reservoirs to be supplied through the pipe 11 to the point of use.

During the time the valve 45 is unseated from the seat 44 and before it is seated on the seat 43 both reservoirs 4 and 5 are connected through the choke 31 to the atmosphere to permit any moisture present in the bottom of either reservoir to be discharged therefrom through the choke 31. Every time the compressor 1 is shut down any moisture present in either reservoir is thus drained to the atmosphere.

After the valve 45 seats on the seat 43, the fluid under pressure remaining in the chamber 29, cooling coil 2, discharge valve chamber 10, pipe 13 and chamber 66 in the cut-off valve 8 will flow to the atmosphere through the choke 31 for re-

leaving the compressor discharge valve of pressure of fluid in chamber 10, i. e., for unloading the compressor, for subsequent starting.

The area of the clearance space between the periphery of valve 45 and the wall of chamber 41 is so related to the venting capacity of choke 31 as to ensure the pressure of fluid in chamber 41 at one side of said valve reducing sufficiently below that in chamber 48 at the opposite side to cause operation of said valve as just described.

When the compressor 1 is started again it will therefore start against atmospheric pressure in the discharge chamber 10. The fluid under pressure discharged from the compressor 1 will flow from the discharge chamber 10 through the cooling coil 2 to chamber 29 and past the valve 34, if open, and through choke 31 to the atmosphere. Since fluid under pressure is being supplied to the chamber 29 more rapidly than it can be exhausted through the choke 31, the pressure in chamber 29 and on the right hand side of the diaphragm 35 will increase until it exceeds that in chamber 51 on the left hand side of said diaphragm. When the pressure on the right hand side of the diaphragm 35 exceeds that on the left hand side, said diaphragm will be deflected toward the left hand until the valve 34 is seated which prevents further flow of fluid under pressure from the chamber 29 to the atmosphere through the choke 31.

With the valve 34 seated, the pressure in the chamber 29 continues to increase until it slightly exceeds that in chamber 41 and the reservoirs 4 and 5, at which time the valve 45 will be forced from its seat 43 and drop by gravity against the seat 44. Fluid under pressure which is being supplied to the chamber 29 by the compressor 1 can now flow to the reservoir 4. At the same time that fluid under pressure is being supplied to the chamber 29, it is also supplied to the chamber 66 of the cut-off valve 8. When the pressure in the chamber 66 is raised sufficiently to overcome the force of the spring 70, the cut-off valve 58 will be unseated and the fluid under pressure present in the small reservoir 4 will flow to the large reservoir 5, in the manner which has already been explained.

Summary

It will now be seen that I have provided a fluid compressing apparatus embodying means for pre-cooling the compressed fluid under pressure before it is forced into the main or storage reservoir and for using this precooled fluid under pressure to cool the compressor discharge valve to keep its temperature below a dangerous value. It will also be seen that I have provided means for unloading the compressor and draining the condensate in each of the reservoirs each time the compressor is shut down.

Having now described my invention what I claim as new and desire to secure by Letters Patent is:

1. In combination, an air compressor comprising a discharge valve disposed in a discharge valve chamber, a first reservoir for cooling and a second reservoir for storing fluid under pressure, an unloading and drain valve device disposed between and connected to said discharge valve chamber and said first reservoir and operable upon the shutting down of the compressor to momentarily drain moisture from each of said reservoirs and to unload said compressor, and a cut-off valve disposed between and connected to said discharge valve chamber and said second

reservoir and operable at one time to close fluid pressure communication through said discharge valve chamber between said first reservoir and said second reservoir and operable upon the establishment of a chosen differential of pressures between said second reservoir and said first reservoir to establish a fluid pressure communication between said reservoirs to equalize the pressures in said reservoirs.

2. In combination, an air compressor comprising a discharge valve disposed in a discharge valve chamber, a first reservoir for cooling and a second reservoir for storing fluid under pressure, a cooling coil connecting said chamber to said first reservoir for cooling the fluid under pressure discharged by said compressor and a cut-off valve controlling a communication between said discharge valve chamber and said second reservoir and operable to successively open and close said communication.

3. In combination, an air compressor comprising a discharge valve disposed in a discharge valve chamber, a first reservoir and a second reservoir, a fluid pressure communication connecting said valve chamber and said first reservoir, a second fluid pressure communication connecting said valve chamber and the said second reservoir, and a cut-off valve disposed in said second fluid pressure communication comprising 30 a differential area piston subject to pressure of fluid in said second reservoir opposing pressure of fluid in said first reservoir and operable to open said second fluid pressure communication upon a chosen preponderance in pressure of fluid 35 in said first reservoir over that in said second reservoir and to close said second fluid pressure communication upon a chosen reduction in the degree of said preponderance.

4. In combination, an air compressor comprising a discharge valve disposed in a discharge valve chamber, a first reservoir for cooling and a second reservoir for storing fluid under pressure, a cooling coil, an unloading and drain valve device connected in series with said coil between 45 said discharge valve chamber and said first reservoir and operative in response to substantial equalization of pressures in said reservoir to momentarily open a drain from said reservoirs and to dissipate fluid under pressure in said discharge valve chamber, and a cut-off valve disposed in a connection between said discharge valve chamber and said second reservoir operative in response to a chosen increase in pressure of fluid in said first reservoir above that in said second reservoir to open a fluid pressure flow communication between said reservoirs for permitting flow of fluid under pressure in the direction from said first reservoir to said second reservoir and for permitting cooling of said discharge valve and 55 discharge valve chamber by fluid under pressure passing through said chamber from said first reservoir to said second reservoir, and operative in response to a reduction in the differential in pressures in said reservoir to a chosen degree to close said fluid flow communication.

5. In combination, an air compressor comprising a discharge valve disposed in a discharge valve chamber, a first reservoir, a cut-off valve disposed between and connected to said first reservoir and said discharge valve chamber and operative to control a fluid pressure communication between said chamber and said reservoir, a second reservoir, a cooling coil and an unloading and drain valve device, said cooling coil and valve device being connected in series

between said valve chamber and said second reservoir, and said unloading and drain valve device comprising means operative upon shutting down of said compressor to unload said compressor, means for momentarily opening a moisture drain from each of said reservoirs upon operation of said valve device, and means for establishing a fluid pressure communication between said reservoirs upon unloading said compressor and terminating said draining.

6. In combination, an air compressor comprising a discharge valve disposed in a discharge valve chamber, a first reservoir open to said chamber for receiving and cooling fluid under pressure compressed by said compressor, a second reservoir for storing fluid under pressure compressed by said compressor, and a cut-off valve device operative in response to the pressure in said first reservoir exceeding that in said second reservoir by a chosen degree to establish a fluid pressure communication between said reservoirs and operative to close said communication upon the pressure in said first reservoir reaching a chosen lower degree.

7. In combination, an air compressor, a first reservoir for receiving and cooling fluid under pressure compressed by said compressor, a second reservoir for storing fluid under pressure, and a cut-off valve device comprising a casing, a valve seat in said casing encircling a fluid flow communication from said first reservoir to said second reservoir, a piston means slidably mounted in said casing subject on one side to pressure of fluid in a control chamber, a valve of smaller area than said piston means projecting from the opposite side thereof for cooperation with said seat to close said communication, a spring urging said valve to said valve seat, a restricted communication connecting said first reservoir to said chamber, and a check valve in said restricted communication for preventing flow of fluid under pressure therethrough in the direction from said chamber to said first reservoir.

8. In combination, an air compressor, a first reservoir, a heat radiating pipe connecting the discharge of said compressor to said first reservoir, a second reservoir, cut-off means operable in response to a chosen differential in pressures in said first and second reservoirs upon an increase in pressure in said second reservoir over that in said first reservoir to establish a fluid flow communication between said reservoirs and operable upon a chosen reduction in said differential to close said communication, an unloading valve device comprising a first means subject opposingly to pressures of fluid in said pipe and atmosphere controlling a vent from said pipe and a second means operable by pressure of fluid in said pipe upon exceeding that in said second reservoir to operate said first means to close said vent and operable upon substantial equalization of pressures of fluid in said pipe and second reservoir to render pressure of fluid in said pipe acting on said first means effective to actuate said first means to open said vent, means controlling a communication between said first and second reservoirs and said pipe including a check valve operable by pressure of fluid in said pipe when in excess of that in said second reservoir to close communication therebetween and to open said first reservoir to said first means and operable upon a reduction in pressure in said pipe below that in said second reservoir to first establish communication between both of said reservoirs and said first means and to then dis-

connect said reservoirs from said first means while retaining said reservoirs open to each other, and a spring acting on said check valve for controlling operation thereof in response to operation of said first means.

9. In combination, an air compressor, a first reservoir connected to said compressor for receiving compressed fluid delivered thereby, a second reservoir, one way flow means connecting said reservoirs for permitting flow of fluid under pressure from said first reservoir to said second reservoir, and a drain valve device disposed between said compressor and said first reservoir and having a fluid pressure communication with said second reservoir, said valve device comprising means operable in response to operation of said compressor to establish a fluid pressure communication between said compressor and said first reservoir, means operable in response to the shutting down of said compressor to establish a fluid pressure flow communication from said second reservoir to said first reservoir and from both of said reservoirs to atmosphere to drain moisture from said reservoirs, and time limiting means operable to close the last mentioned communication after a chosen interval of time.

10. In combination, an air compressor having a compressed air discharge chamber, a first reservoir connected to said chamber for receiving and precooling fluid under pressure delivered by said compressor, a fluid pressure storage reservoir, and a pressure limiting cut-off valve device disposed between and connected to said reservoirs, said valve device comprising a first means controlling a communication between said reservoirs and a second means for rendering said first means operable in response to a chosen differential between the pressures in said first reservoir and in said storage reservoir to effect a flow of fluid under pressure from said first reservoir to said storage reservoir, and for actuating said first means for closing said communication upon a reduction in said differential to a degree lower than said chosen differential.

11. In combination, an air compressor having a compressed air discharge chamber, a first reservoir connected to said chamber for receiving and precooling fluid under pressure delivered by said compressor, a fluid pressure storage reservoir, a pressure limiting cut-off valve device disposed between and connected to said reservoirs, said valve device comprising a first means controlling a communication between said reservoirs and a second means for rendering said first means operable in response to a chosen differential between the pressures in said first reservoir and in said storage reservoir to effect a flow of fluid under pressure from said first reservoir to said storage reservoir, and for actuating said first means for closing said communication upon a reduction in said differential to a degree lower than said chosen differential, and means operable upon shutting down of said compressor to disconnect said first reservoir from said chamber and open said chamber to atmosphere and to also establish a fluid flow communication from said first reservoir to said storage reservoir.

12. In combination, an air compressor comprising a discharge valve disposed in a discharge valve chamber, cooling means for cooling fluid under pressure compressed by said compressor through said chamber, a reservoir for storing fluid under pressure, and means responsive to a chosen differential between pressure in said cooling means and reservoir to establish a

11

communication between said cooling means and reservoir and responsive to a lower differential to close said communication.

13. In combination, an air compressor, a first reservoir for cooling fluid under pressure compressed by said compressor, a second reservoir for storing fluid under pressure, means operable upon shutting down of said compressor to establish a fluid flow communication from said first reservoir to said second reservoir for 10 equalizing pressures in said reservoirs, and means operable in response to substantial equalization of pressures in said reservoirs to unload said compressor.

14. In combination, an air compressor, a first 15 reservoir for cooling fluid under pressures compressed by said reservoir, a second reservoir for storing fluid under pressure, means operable upon shutting down of said compressor to equalize pressures of fluid in said reservoirs, and 20 means operable in response to substantial equalization of pressures in said reservoirs to drain moisture from said reservoirs.

12

15. In combination, an air compressor, a first reservoir for cooling fluid under pressure compressed by said reservoir, a second reservoir for storing fluid under pressure, means operable upon shutting down of said compressor to equalize the pressures of fluid in said reservoirs, and means operable in response to shutting down of said compressor and the equalization of pressures in said reservoirs to unload said compressor and momentarily open a liquid drain from said reservoirs.
